United States Patent Office

Des. 196,843
Patented Nov. 12, 1963

196,843

BOOK END

Douglas R. Cleminshaw and Kenard E. Uron, Syracuse, N.Y., assignors to Gaylord Bros., Inc., Syracuse, N.Y., a corporation of New York

Filed Apr. 11, 1963, Ser. No. 74,402

Term of patent 14 years

(Cl. D33—3)

FIG. 1.

FIG. 2.

FIG. 3.

FIG. 4.

FIG. 5.

FIG. 6.

FIG. 7.

FIG. 8.

FIG. 1 is a front elevational view of a book end embodying our new design;

FIG. 2 is a view thereof in side elevation;

FIG. 3 is a vertical cross-sectional view as taken on line 3—3 of FIG. 1;

FIG. 4 is a top plan view;

FIG. 5 is a bottom plan view;

FIG. 6 is a horizontal cross-sectional view as taken on line 6—6 of FIG. 1;

FIG. 7 is a view in rear elevation; and

FIG. 8 is a perspective view.

We claim:

The ornamental design for a book end, substantially as shown.
